The ornamental design for a work vehicle cabin, as shown and described.

DESCRIPTION

FIG. 1 is a top, front, left diagrammatic perspective view of a work vehicle cabin showing our new design with exemplary work vehicle environment;

FIG. 2 is a top, rear, left perspective cut-away view thereof;

FIG. 3 is a top plan view thereof;

FIG. 4 is a rear end view thereof;

FIG. 5 is a left side elevational view thereof;

FIG. 6 is a right side elevational view thereof;

FIG. 7 is a top, front, left diagrammatic perspective view of work vehicle cabin showing another aspect of our new design with exemplary work vehicle environment;

FIG. 8 is a top, rear, left perspective cut-away view thereof;

FIG. 9 is a top plan view thereof;

FIG. 10 is a rear end view thereof;

FIG. 11 is a left side elevational view thereof; and,

FIG. 12 is a right side elevational view thereof.

The broken lines shown illustrate portions of the work vehicle cabin that form no part of the claimed design, and, in FIGS. 1 and 7, the broken lines illustrate environmental structure that forms no part of the claimed design.

The nature of this product is a work vehicle, such as used in the construction and forestry industries.
